CLAIM

The ornamental design for a bag, as shown and described.

DESCRIPTION

FIG. 1 is a top, front, left perspective view of a bag showing our new design;

FIG. 2 is a front view thereof;

FIG. 3 is a rear view thereof;

FIG. 4 is a left side view thereof;

FIG. 5 is a right side view thereof;

FIG. 6 is a top, front, left perspective view of an alternative claimed configuration of a bag showing our new design;

FIG. 7 is a top, front perspective view thereof;

FIG. 8 is a top, front, left perspective view of an alternative claimed configuration of a bag showing our new design; and,

FIG. 9 is a top, front perspective view thereof.

The portions of the bag shown in broken lines form no part of the claimed design. The grayscale contrast represents a contrast in appearance only and does not represent any particular color, material, texture or finish. Applicant recognizes that inventive aspects of the embodiments include grayscale and line drawing representations thereof, and Applicant reserves the right to amend this application and/or to file one or more divisional and/or continuation applications to specifically claim or disclaim such arrangement in the present application and in any divisional and/or continuation applications.
